CLAIM

The ornamental design for a notebook computer shell, as shown and described.

DESCRIPTION

FIG. 1 is a perspective view of a notebook computer shell showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and

FIG. 8 is an enlarged detail view showing a portion of the design as indicated in the area '8' in FIG. 7;

FIG. 9 is an enlarged detail view showing a portion of the design as indicated in the area '9' in FIG. 7; and,

FIG. 10 is a back perspective view of the notebook computer shell of FIGS. 1-7, shown in an alternate configuration with its handle open.

The broken lines shown in the drawings are for the purpose of illustrating portions of the notebook computer shell that form no part of the claimed design. The additional set of broken lines showing enlarged detail views in FIGS. 7-9 are for annotative purposes and form no part thereof.
